UNITED STATES PATENT OFFICE.

DANIEL W. MARVIN, OF SYRACUSE, NEW YORK.

IMPROVEMENT IN FLOUR-SIFTERS.

Specification forming part of Letters Patent No. 151,232, dated May 26, 1874; application filed February 17, 1874.

To all whom it may concern:

Be it known that I, DANIEL W. MARVIN, of Syracuse, in the county of Onondaga and State of New York, have invented a new and useful Improvement in a Flour Safe and Sifter, of which the following is a specification:

My invention relates to a combined storage bin and sifter in which flour is kept and sifted as required for use; and my said invention consists of a sieve hinged to be opened downward from the bottom of the bin, in combination with the agitator suspended by a collar, whereby the agitator is maintained in position within the funnel bottom band of the bin when the sieve is opened and turned down to free it of foreign matter, making in effect a hinged sieve separate from and independent of the agitator which rests upon said sieve, and by which the latter can be opened and closed without moving the agitator with the sieve.

In the accompanying drawings, Figure 1 represents a vertical section of a flour bin and sifter embracing my invention, and Fig. 2 a horizontal section of the same.

The bin A has a capacity for holding fifty or more pounds of flour, with a semi-cylindrical or horizontal flat sieve, B, open at the top, and forming, in connection with the inclined sides a, the bottom of the bin. A horizontal agitator, C, is arranged to be revolved within or upon the open sieve by a crank-handle, D, on a perpendicular shaft, E. The perpendicular shaft E is attached to the agitator C by a loose joint, b, so as to allow the agitator C to automatically accommodate itself to the surface of the sieve, upon which it rests, whether the shaft is perpendicular thereto or otherwise, when rotated. The axis of the perpendicular shaft is in the cover of the bin, and in the center of the wheel-agitator C resting in the sieve. The agitator rotates within the hoop e of the sieve, and is held in position by said hoop.

The sieve B is hinged at one side to the funnel-bottom a, for the purpose of allowing it to be dumped, and it is secured to its closed position by a hook or hooks, d, at its free side. In unfastening this hook the sieve will swing down and back upon its hinges against the wall or bottom f, and empty itself of all matter which may collect thereon. In this dumping action the agitator remains intact, being suspended by a collar, e, on its upper bearing, as the sieve is opened and closed below it for the purpose stated. A drawer, F, about the size of a six-quart pan, to receive the sifted flour, is placed in the bottom of the box beneath the sieve, and the cover G of the bin is locked, so that the flour will be safe from loss, dirt, or vermin. The turning of the agitator C sifts the flour, and when the drawer is filled it may be removed for use, thus combining with a flour-bin a sifter and receiving and measuring pan, and rendering it very convenient for use. When the agitator is used with a horizontal axis it is operated at the side by a crank; but as shown it is a skeleton ring with arms g, open spaces h, and an annular rim, i, with a vertical flange, j, fitting within the hoop e, which serves as the guide and retainer for the agitator in position upon the sieve, the flat surface of the one moving upon the flat surface of the other.

I claim—

The sieve B, hinged to be opened downward from the bottom of the bin A, in combination with the agitator C, suspended by the collar e, to maintain the agitator in position within the band e, when the sieve is opened and turned down, as shown and described.

DANIEL W. MARVIN.
